ELECTRIC CLOCK SYSTEM

Clinton E. Larrabee, Binghamton, N. Y., assignor,
by mesne assignments, to International Business
Machines Corporation, New York, N. Y., a
corporation of New York

Application July 16, 1932, Serial No. 622,903

3 Claims. (Cl. 58—24)

This invention relates to electric clock systems and more particularly to electric clock systems of the minute impulse type, which are controlled or supervised by a master clock.

Frequently, two master clocks are used in connection with the supervision of electric clock systems in which one of the two master clocks is carried as a spare or reserve clock to be used in the event of the other master clock becoming incapacitated. This is generally taken care of by a throw-over switch which is operated manually, but this is not entirely satisfactory as the failure of the clock can only be detected when the failure of the system is noted, at which time, who ever is in charge of the system must immediately go to the control switches and throw the control from the master clock, which has failed, to the other master clock which is intended to act in such emergencies. The present invention relates to accomplishing this throw-over automatically upon the failure of the master clock.

It is therefore one object of this invention to provide a device for automatically throwing the control of an electric clock system from one master clock to another master clock.

Another object of this invention is to provide a device for detecting the failure of a master clock, and for giving a warning upon the failure of said clock.

Still another object is to provide an electric clock system controlled by a supervising master clock and a device operable by said master clock and an auxiliary master clock which determines which of the two master clocks shall control the system.

A further object is to provide a device operable by a supervising master clock and an auxiliary master clock in which the failure of the supervising master clock causes the control of an electric clock system to be transferred to the auxiliary master clock and causes a signal or warning to be given and in which the failure of the auxiliary clock causes only a warning signal to be given.

A still further object is to provide a differentially operated mechanism operated from two master clocks in which the failure of one of the master clocks will cause the control of an electric clock system to be transferred to the other master clock.

Other objects and advantages of this invention will be apparent from the specification and the accompanying drawings which show one embodiment of this invention and wherein similar reference numerals indicate similar parts and wherein the drawings:

Fig. 1 shows a general front elevation of a suitable master clock.

Fig. 2 shows a side detailed view of the differential mechanism controlled by two magnet driven units.

Fig. 3 is a detail view of the transferring device taken on line 3—3 of Fig. 2.

Fig. 4 shows the wiring diagram of such a system.

The type of electric clock system shown in the 10 preferred embodiment of the specification and as illustrated is an hourly supervised or synchronized system such as shown in the patent to J. W. Bryce, No. 1,687,491. The master clock may be of any desired form, such for example, as is shown 15 in the patent to J. W. Bryce, No. 1,390,018.

Referring now to Fig. 1, the master clock includes the usual time train adapted to drive the minute arbor 10 which makes one revolution per hour. The usual verge mechanism 11 is provided. 20 Fixed to the minute shaft are a pair of cams 12 and 13 which cams are shaped in position to control a pair of contacts 14 on which the position of the upper contact and its arm is controlled by cam 13 and the position of the lower contact and 25 its arm is controlled by cam 12.

Also fixed to the minute arbor 10 is a cam 15 which is adapted to open and close two pairs of contacts 16 and 20. In addition, the master clock is provided with the usual minute impulse contacts 17 which are controlled in the usual way from a cam 18 making one revolution per minute or otherwise, as is the custom in clocks of this sort. For advancing or stepping forward the secondary clocks, there is provided quick acting contacts 19, 35 which are preferably operated by attaching on the verge mechanism 11. These contacts 19 will close at every swing of the pendulum, the bob of which would be attached to the lower end of the pendulum rod 21.

The secondary clock movements which would be controlled by this master clock are shown diagrammatically in Fig. 4 at 22. The cam 23 on each of the secondary clocks is fixed to the minute arbor and actuates the contacts 25 and 26 by 45 means of the cam follower 24 in identically the same manner as described in the patent to Bryce No. 1,687,491. The master clock through its contacts 14, 16, 17 and 19 sends out normal impulses and rapid impulses during the synchronizing period over the wires A and B for the normal operation and synchronization of the secondary clocks 22 in the same manner as described in the previously mentioned patent.

In the operation of this invention two master 55

clocks are used, one of which will hereinafter be described as the supervising master clock and the other as the auxiliary master clock. Both of these master clocks are identical and have the same contacts which are timed in the same manner. In Fig. 4 the contacts and cams and wiring of the two master clocks are generally shown at 27 and 27a. Under normal conditions the supervising master clock 27 controls the operation of the secondaries and only upon the failure of this supervising clock is the auxiliary master clock brought into the system to then control the secondary clocks. The switch-over of the control of the secondary units of the system is effected by the operation of a multicontact relay. This multicontact relay is effected only upon the failure of the master clock, which causes contact 28 to close thus energizing magnet 29 which is the relay magnet of the multicontact relay. The contact 28 which is normally open is also associated with another normally open contact 30 and a normally closed contact 31. One of the blades 32 extends outwardly beyond the other blade and coacts with an insulated member 33 fixed to an arm 34 pivoted at 35 to a fixed plate 36 on which are also mounted the previously mentioned contacts. Substantially in the center of the arm 34 is a cam follower 37 which wipes on a cam 38. When the clock system is in the correct operative condition the cam wiper 37 normally rests in a notch 39 on said cam but with the stopping of either one of the clocks this cam is adapted to rotate in a clockwise or counter-clockwise direction according to whether the auxiliary master clock or the supervising master clock has stopped. The manner in which this cam is rotated will be explained later.

If the supervising master clock stops the cam will move one step in a counterclockwise direction as viewed in Fig. 3 causing contact 31 to open and contacts 30 and 28 to close and once this has taken place the cam 38 will move no further. If the auxiliary master clock fails the cam 38 will move one step in a clockwise direction causing contacts 30 to close and contact 31 to open. It will be noted that contact 28 does not close in this event as the arm 34 is not actuated to the same extent when the cam moves clockwise as it is when the cam moves counterclockwise. This is due to a cam plate 40 which is fixed to one face of the cam 38 this plate having a camming surface adjacent to the cam wiper 37 and extending beyond the periphery of the cam 38 so that when the cam 38 moves counterclockwise the cam wiper 37 cooperates with the cam plate 40 to move the arm 34 in a clockwise direction about its pivot point 35 a sufficient distance so that the insulated member 33 cooperating with the blade 32 will lift that blade opening the contact 31 and closing contacts 30 and 28. If, on the other hand, the cam 38 moves in a clockwise direction, the cam follower moves out of its notch on to the periphery of the cam 38 which causes it to move the cam wiper less than half the distance as in the previous case thus causing only contact 30 to close and contact 31 to open but not moving the arm 34 sufficiently to close contact 28.

The movement of the cam 38 is provided through the differential operation of mechanisms under the direct control of the two master clocks. These two mechanisms are generally shown in Fig. 2 and consist of two secondary clock movements which may be mounted together by spacing studs 51 extending between and rigidly fastened to front plates 52 and 52a which constitute

the two front plates of the secondary movement. The secondary movement may be of any suitable ratchet and pawl design of which there are many to choose from.

In this application I have preferred the embodiment of the secondary movement which is shown in my Patent No. 1,821,100, dated September 1, 1931, which describes in detail the operation of the secondary movement in which electrical impulses delivered each minute to magnets 53 and 53a operate a ratchet and pawl mechanism to rotate the ratchets 54 and 54a. These ratchet wheels are fixed to shafts 55 and 55a and rotate these shafts in opposite directions at relatively the same speed; that is, each magnet receives impulses at one minute intervals although they might not necessarily coincide. Fixed to shaft 55 is a bevelled gear 56 and mounted loosely on the shaft 55 at the extremity of said shaft where the diameter is reduced is a bevelled gear 57 having an axially extended portion 58 which abuts the shoulder formed by the larger diameter of the shaft 55 and which holds the bevelled gear in spaced relation to the bevelled gear 56. At the extreme end of the shaft 55, said shaft is provided with a still smaller and threaded diameter on which is screwed a knurled nut 60 for holding the gear 58 upon the shaft. Such construction is that used generally for holding the minute hand on the minute arbor of a clock.

Fixed to the bevelled gear 57 is a bifurcated member 61 which engages an L-shaped arm 62, one end of which extends through the bifurcation of said bifurcated member and the other end of which is fixed by means of a knurled nut 60a to the shaft 55a. Two planetary bevelled gears 65 are rotatively mounted within a supporting member 66 (see Fig. 3) to which supporting member is fixed the cam 38. The rotatively mounted bevelled gears 65 each mesh with both of the bevelled gears 56 and 57 thus providing a differential gear mechanism capable of indicating differences of relative motion of the two gears 56 and 58. Gear 58 is operated in one direction by the secondary movement 50a, whereas, gear 56 is operated in the other direction by the secondary movement 50.

Thus if both of these movements operate the respective gears on their arbors in opposite directions and at the same relative rate there will be no change in the position of the cam 38 due to the free rolling action about the axis of the planetary gears 65, whereas, if one or the other of the secondary movements stop the cam 38 will rotate in either one direction or the other depending upon which one of the two mechanisms are caused to stop. As this differential action is old and fully understood by any one at all skilled in the art, it is believed that no further or more detailed description need be given.

Turning now to Fig. 4, contact 17 closing every minute by virtue of the operation of the cam associated therewith, all of which is described in the patent to Bryce No. 1,687,491 previously referred to, operates relay magnet 18 once each minute thereby closing relay contacts 19 each minute to transmit impulses from the positive supply line through line 12, contact 19, to the secondary clock line A and then through one of the contacts associated with the secondary clock when closed, through the magnet which operates the secondary clock and which are diagrammatically indicated at 13 to the ground which is in turn connected to the negative part of the line. It is to be understood that alternating current can be

used in this connection as well as direct current but for the convenience of tracing circuit, the terms positive and negative side will be used.

The operation of the relay coil 70 is effected 5 through the following circuits. From the positive supply line through wire 14, switch 15, lower contact blade 16, back contact 17, wire 18, multi-relay contact 19, wire 80', relay coil 80, contact 17, wire 81, multi-relay contact 82, relay coil 70 and 10 back to the negative side of the line.

It will be noticed that the minute impulses which operate master relay coil 70 which in turn operates the secondary clock also operates the relay coil 80 which is in series with said master relay 15 coil to close contacts 80a once each minute. The closing of said contacts 80a each minute initiates minute impulses which are transmitted to the differential driving magnet 53 as follows: from the positive supply line through wire 114, contacts 20 80a, driving magnet 53, wire 115, closed contacts 81, wires 98 and 99 to the negative supply line.

The corrective or synchronizing feature of the secondary circuit is taken care of in the same manner as shown in the Bryce Patent No. 1,687,491 25 previously referred to in which the B wire of the secondary circuit is periodically opened by the opening of relay contacts 83 thus preventing the impulses initiated by closing of relay contacts 71 being transmitted over the B wire. This is accomplished by connecting the relay magnet 84 in 30 circuit with the contact 14 as is shown in the Bryce patent thus establishing a circuit from the positive source of supply to wire 14, switch 15, line 85, contact 14, wire 86, multi-relay contact 87, wire 35 88, relay magnet 84 and back to the negative side of the line. Thus the closure of contact 14 at its proper interval will break the contact at 83 providing the bottom contacts of the multi-contact relay are closed. The rapid impulses for setting 40 slow clocks ahead are initiated by the operation of the contact 19 which closes every second or two seconds with the swing of the pendulum and is produced by bringing this contact into circuit by the closure of contact 16 in which a circuit will 45 be established from the positive side of the supply line, through wire 14, switch 15, contact 16, contacts 19, resistance R1, wire 81, contact 82, master relay magnet 70 to the negative side of the supply line.

The back contact 17 is provided in addition to the contacts shown in the Bryce patent, in order to cut the relay magnet 80 and therefore the differential driving magnet 53 out of the circuit when rapid impulses are sent through so that the rapid 50 impulses will not affect the driving magnet and as the relay magnet 80 is normally in series with the relay magnet 70, a resistance R1 is provided in the line to replace an equivalent resistance when the operations of the contacts 16 and 17 cut in 55 the resistance R1 and cut out the relay magnet 80.

The above explains the normal operation of the secondary clock system from the master clock. During this normal operation the auxiliary clock also operates but as its control contacts are connected to the upper contacts of the multi-contact relay which are now open, it has no effect on the secondary clock system. There is one exception to the previous statement regarding the multi-contact relay, and that is, that the lower relay 65 contact 90 is connected in circuit with the minute impulse contact 11a of the auxiliary master clock to operate the driving magnet 53a of the differential mechanism as follows: from the positive side of the supply line, through wire 91, wires 92 70 and 93, minute impulse contact 11a, wires 94 and 75

95, normally closed relay contacts 96, wire 97, multi-contact relay contacts 90, differential driving magnet 53a, wires 110 and 98 back to the negative supply line. Both drives of the differential mechanism are thus simultaneously operated as 5 long as the master clock and the auxiliary master clock are running.

Relay magnet 100 connected with the auxiliary master clock is in circuit with the normally closed contact 101 from the positive side of the supply 10 line, through lower contact 101, through relay magnet 100 to the negative side of the supply line thus keeping this magnet normally energized so that relay contacts 96 are normally closed.

The purpose of this is to prevent the rapid 15 correcting impulses from the auxiliary master clock contact 19a from effecting the differential drive magnet 53a during the period when contact 16a closes to cut the rapid correcting impulses into circuit as when contact 16a closes contact 20 101 will open whereupon relay magnet 100 will become deenergized opening relay contacts 96 and thus breaking the circuit to the differential driving magnet 53a. As contacts 77 and 101 of the two master clocks open only between minute 25 20 impulses of their respective master clocks the two differential driving magnets will not be cut off from any of the regular minute impulses initiated by either of the master clocks.

In the operation of the differential mechanism, 30 let it be assumed that the supervising master clock, the circuit of which is shown at the left in Fig. 4 has stopped. In this case as contact 17 no longer functions the differential driving magnet 53 will no longer receive minute impulses to 35 drive its respective side of the differential mechanism, whereas, the differential driving magnet 53a will continue to receive the minute impulses from the auxiliary master clock, the result being that upon the first or second impulse received by 40 the driving magnet 53a after the discontinuance of the operation of driving magnet 53, the cam 38 will be moved in a counterclockwise direction and the cam wiper 37 will ride up on the cam plate 40 as previously described (see Figs. 3 and 4) opening contact 31 and closing contacts 30 and 28. 45 The opening of contact 31 breaks the circuit through the differential drive magnet 53. The closing of contacts 28 and 30 cause the multi-contact relay 29 to become energized through the 50 following circuit: From the positive supply line, through wire 102, multi-contact relay magnet 29, wire 103, contacts 28 and 30, wires 98 and 99 to the negative supply line.

This circuit being established, the armature of 55 the multi-contact relay is attracted to the magnet, thus opening the relay contacts 90, 79, 82, 81 and 104, which are the lower contacts and closing the upper contacts 82a, 87a, and 104a. The opening of contact 90 breaks the circuit to the 60 differential driving magnet 53a thus stopping the cam 38 from further movement and leaving its associated contacts 28 and 30 in a closed position and with contact 31 opened. The closure of contacts 82a and 87a connect the clock control 65 relays 70 and 84 to the auxiliary master clock. The minute impulse contact 11a operates the relay magnet 70 through the following circuit: from the positive supply line through wires 91, 92 and 93, contact 11a, wire 94, contact 82a now closed, 70 wire 105, relay magnet 70, back to the negative side of the supply line. Contacts 14a control the relay magnet 84 through the following circuit. From the positive side of the supply line, through wires 91 and 92, contacts 14a, wire 106, contacts 75

87a (now closed), wire 88, relay magnet 84, and back to the negative side of the supply line. Thus the two system control relays are operated from identical correspondingly timed contacts in the 5 auxiliary master clock as they were in the supervising master clock. The closure of contact 104a causes a suitable signal to be given to announce the failure of the master clock. This may be a sound signal, such as a bell or a horn, or it 10 may be a light signal. In the preferred embodiment, a light signal is diagrammatically shown and is operated from the following circuits: From the positive side of the supply line, through wire 107, electric light 108, wire 109, upper contact 104a (now closed), wires 110 and 88, and back to the negative side of the supply line.

As previously stated, when an attendant or service man has answered the trouble warning of light 108 and has corrected the condition and has 20 set the main operating master clock again into operation, the cam 38 is reset which will open the contacts 28 and 38 thus deenergizing multi-contact relay magnet 28.

The deenergization of this relay causes the 25 lower contact of this relay to again be closed whereby the driving magnet 53 and 53a will resume operation under control of their respective master clocks and the secondary clock system will resume operations under the control of the supervising master clock.

In the event of failure of the auxiliary master clock the minute impulses initiated therefrom will cease thereby terminating the operation of the driving magnet 53a, which will cause the cam 35 38 to rotate in a clockwise direction upon the next succeeding impulses from the supervising master clock transmitted to the driving magnet 53. The rotation of the cam 38 in a clockwise direction will cause the cam wiper 37 to ride up 40 on the periphery of the cam 38 causing contact 31 to open and contact 38 to close but as the rotation of the cam 38 in this direction does not lift the cam wiper as far as it did in the previous instance, the contact 28 will not close. In this 45 case, the supervising master clock is operating satisfactory and therefore the stopping of the auxiliary master clock does not require any transfer of the secondary clock system, therefore, the multi-contact relay is not affected which is the 50 purpose of maintaining contact 28 open in the event of failure of the auxiliary master clock. The opening or contact 31 again breaks the circuit to the differential driving magnet 53 and as the driving magnet 53a has already stopped the 55 cam 38 will rotate no further after the contact 31 has opened.

The closing of contact 38 causes the warning signal to operate as previously described and

through the following circuit: from the positive side of the supply line, through wire 107, electric light 108, wire 109, lower contact 104 (now closed), wire 111, contact 38, wire 88, and back to the negative side of the supply line.

In this case also, after the attendant has taken heed of the warning and has corrected the trouble in the auxiliary master clock the same is set to time and continues with its operation and the cam 38 is reset preparatory to operating again to 10 give warning upon the failure of either of the master clocks.

Only in the event of both master clocks stopping at the same time will this throw-over device fail to operate but this constitutes such a 15 remote coincidence that it is not necessary to consider such a possibility in commercial application.

While the fundamental and novel features of the invention, as applied to a single modification is shown and described and pointed out, it will be understood that various omissions and substitutes and changes in the form and details of the device illustrated and in its operation may be made by those skilled in the art without departing from the spirit of the invention. I intend to be limited therefore only as indicated by the scope of the following claims.

What is claimed is as follows:

1. An electric clock system including two master clocks and a plurality of secondary clocks controlled thereby, a differential mechanism operable by both master clocks conjointly, contacts operable by said differential mechanism for transferring the control of said secondary clocks from one master clock to the other.

2. An electric clock system including two master clocks and a plurality of secondary clocks controlled thereby, means for transferring the control of said secondary clocks from one master clock to the other, said means comprising a member operable from each of the said master clocks, a cam operable by the relative movement of said members, contact mechanism operable in accordance with the movement of said cam, and a relay operable by said contacts for effecting the transfer of the control of said secondary clocks from one master clock to the other.

3. An electric clock system comprising two master clocks, a plurality of secondary clocks adapted to be operated by one or the other of said master clocks, means operated conjointly by both master clocks and means controlled by said last named means for selecting the one or the other of said two master clocks for operating the secondary clocks.

CLINTON E. LARRABEE.
